UNITED STATES PATENT OFFICE.

BENJAMIN W. HANLE, OF ELIZABETH, NEW JERSEY, ASSIGNOR TO EAGLE PENCIL COMPANY, OF NEW YORK, N. Y., A CORPORATION OF DELAWARE.

DESIGN FOR A FOUNTAIN-PEN HOLDER.

Application filed June 27, 1928. Serial No. 27,293. Term of patent 14 years.

To all whom it may concern:

Be it known that I, BENJAMIN W. HANLE, a citizen of the United States of America, residing at Elizabeth, in the county of Union and State of New Jersey, have invented a new, original, and ornamental Design for a Fountain-Pen Holder, of which the following is a specification, reference being had to the drawing accompanying and forming a part thereof.

I claim—

The ornamental design for a fountain pen holder, as shown.

In testimony whereof I hereto affix my signature.

BENJAMIN W. HANLE.
